UNITED STATES PATENT OFFICE.

JOHN J. MANNING, OF GREAT BARRINGTON, MASSACHUSETTS.

METHOD OF AND APPARATUS FOR EXHAUSTING THE AIR AND EXTRACTING THE WATER FROM THE SUCTION-BOXES OF PAPER-MACHINES.

SPECIFICATION forming part of Letters Patent No. 282,097, dated July 31, 1883.

Application filed June 20, 1883. (No model.)

To all whom it may concern:

Be it known that I, JOHN J. MANNING, a citizen of the United States, and a resident of Great Barrington, in the county of Berkshire and State of Massachusetts, have invented certain new and useful Improvements in a Method of and Apparatus for Exhausting the Air and Extracting the Water from the Suction-Boxes of Paper-Machines; and I do hereby declare that the following is a full, clear, and exact description of the invention, which will enable others skilled in the art to which it appertains to make and use the same, reference being had to the accompanying drawings, which form a part of this specification, and in which—

Figure 1 is a side elevation of so much of a paper-machine of the "Fourdrinier" pattern as is necessary to illustrate the application of my invention with my apparatus in operative position; and Fig. 2 is a vertical sectional view of my improved steam-jet pump, which is used in connection with and forms a part of my apparatus.

Similar letters of reference indicate corresponding parts in both the figures.

In the manufacture of paper on machines of the so-called "Fourdrinier" type or pattern, as well as on so-called "cylinder" machines, the preliminary process consists in extracting the water from the paper-pulp while it is traveling with the web of wire-cloth or felt over the vacuum-boxes or suction-boxes, which form parts of that class of machines. By the means heretofore employed for this purpose it has been found impossible to use the water drawn by the suction-boxes from the pump over again, as the suction-water, containing resin and other ingredients in solution, will ferment and form a soapy slime, which will stick to the inside of the pipes when the machine is stopped to change to other widths or colors of paper, and, after again starting the machine, this slime, breaking away from the walls of the pipes, is apt to leave black spots upon and otherwise disfigure the paper. Where fresh water is used it will be noticed that at times it is more or less dirty, thus causing various shades in the paper, which is of course also objectionable.

The object of my improvement is to use the suction-water over and over again, thereby

saving the chemicals and other ingredients contained in it, which have heretofore gone to waste. I have found by experiment and actual analysis that the water drawn from the suction-boxes contains from five to fifteen per cent. of coloring-matter, from ten to forty per cent. of the alum which is used for sizing, from three to ten per cent. of resin, and where clay is used from ten to forty per cent. of it is drawn with the suction-water into the boxes.

My invention therefore consists, first, in an improved method of exhausting the air and extracting the water from the vacuum-boxes or suction-boxes; secondly, in the construction and combination of parts of the apparatus, as a whole, used for that purpose; and, thirdly, in the improved construction and combination of parts of a graduating steam-jet pump adapted to be used in connection with, and forming an operative part of, my apparatus.

In the accompanying drawings, A, A', and A² are the vacuum-boxes or suction-boxes of a machine employing three of these, the first two of these boxes being located before the dandy-roll (shown at N) and connected by a pipe, B, running at an angle of about fifteen degrees, to the discharge-pipe C of the third or last box, A². The inclined pipe B is provided with valves D D, for regulating the amount of water to be taken out of the sheet of pulp or fiber before it passes under the dandy. The object of connecting-pipe C, through which suction-box A² discharges, with the first two boxes in this manner is to prevent the use of fresh water in "priming" pipe C, inasmuch as the water from boxes A and A' will act as a primer for box A². The lower end of pipe C extends down to the floor, where it is connected by an elbow, C', to a horizontal pipe, E, leading to and connecting with the inlet of the pump F. The construction of the latter, which is shown in detail in Fig. 2 of the drawings, will be hereinafter more fully described, and from the opening or outlet in its upper end extends the discharge-pipe I, which is connected or coupled at its upper end to a pipe, J, passing transversely across the machine to the back part of the same, where it discharges into the water box or reservoir K, which is provided with an overflow-

pipe, L. From the water-box K the water may be fed into the fan-pump box M through the valve K'.

The pump consists of a spherical casing or globe, F, made of metal or other suitable material, having an inlet at its lower end and a discharge-opening at its upper end, which is suitably connected with or coupled to the discharge-pipe I. This globe is provided with a transverse steam-pipe, G², which by preference is made tapering, and provided at its outer or reduced end with the blow-off cock H. At its large end the steam-pipe is connected to another pipe, G, through which steam is fed from the boiler, the flow of steam being regulated by means of the valve G'. The transverse steam-pipe G², inside of the globe, is provided with a conical or tapering nozzle, P, pointing upwardly. Inserted over this nozzle is the movable or adjustable graduating-nozzle Q, which is in the shape of a double funnel contracted at its middle part, Q'. This adjustable nozzle is provided with a screw-threaded collar, R, fitting into the threaded seat R', in which it may be fixed in its adjusted position by means of the threaded jam-collar S. By unscrewing the latter it will be seen that the adjustable nozzle Q, with its collar R, may be screwed up or down in its seat, so as to adjust its position relative to the fixed nozzle P, and after it has been properly adjusted it may be fixed in its position by tightening down the jam-collar S.

I prefer to attach the discharge-pipe I to the pump by means of a jam-collar, T, which bears against the lower flanged end of the discharge-pipe, a packing-ring (shown at U) being inserted between the flange of the discharge-pipe and its seat. Other means may, however, be provided for coupling the inlet-pipe and discharge-pipe to the spherical chamber of the pump, if desired.

The operation of the apparatus is as follows: To start the suction the valve G' is opened and the adjustable nozzle Q is adjusted, in the manner described, to suit the amount of the vacuum required according to the pressure of steam. The position of this adjustable nozzle may also be graduated to regulate the amount of water to be passed through it in a given period—that is to say, if a greater flow of water is demanded, nozzle Q is adjusted so as to increase the distance between its enlarged lower end and the top of the fixed nozzle, while, if a strong jet of steam but less water is required, it is adjusted in the opposite direction, so as to decrease the distance between it and the fixed nozzle. The water of condensation which accumulates in the steam-pipe should be blown off, when required, through the blow-off cock H, to prevent discoloration of the paper if it should become mixed with the suction-water, as it is usually charged with oxides to a greater or less extent. As the water is drawn from the suction-boxes into the pump it is charged with a soapy slime, formed in the manner described at the outset of this speci-

fication. This slime, however, will not adhere to the pipes, inasmuch as these have become partially heated, and as it enters the spherical chamber inside of the globe with the suction-water, and is blown up through the contracted middle part of the adjustable nozzle, it is thoroughly dissolved and mixed with the water at the point where the contracted nozzle again expands, so that I have found by actual experiment that the water discharged into the water-box K is absolutely free from slime, and forms a clear and thin liquid, adapted to be used over again without occasioning the least discoloration to the paper, or otherwise acting injuriously upon the pulp.

It will be seen that I use only one pump for all the boxes, thus preventing the undue heating of the pipes, which results from the use of a pump or ejector for each separate box.

Having thus described my invention, I claim and desire to secure by Letters Patent of the United States—

1. The hereinbefore-described method of exhausting the air and extracting the water from the vacuum-boxes or suction-boxes of paper-machines, which consists in connecting the first boxes before the dandy to the discharge-pipe of the last box by an inclined pipe provided with valves for regulating the flow of air and water through it, and connecting the discharge-pipe of the last box to a single suction-pump, substantially as and for the purpose shown and set forth.

2. In a paper-machine, the combination of the vacuum-boxes or suction-boxes A, A', and A², inclined branch pipe B, having valves D, discharge-pipe C, suction-pump F, and discharge-pipe I J, substantially as and for the purpose shown and set forth.

3. The graduating steam-jet pump herein shown and described, the same consisting of the globe F, having an inlet at its lower end, an outlet at its upper end, and provided with the threaded seat R', transverse fixed steam-pipe G², having the fixed conical nozzle P, blow-off cock H, adjustable nozzle Q, contracted at Q', and provided with the threaded collar R, adapted to work in the seat R', and jam-collar S, all constructed and combined substantially as and for the purpose shown and set forth.

4. In a paper-machine, the combination, with the vacuum-boxes or suction-boxes, of an inclined pipe discharging from the first box or boxes before the dandy into the discharge-pipe of the last after the dandy, whereby the boxes are successively primed by the charged suction-water from the first box, substantially in the manner and for the purpose shown and set forth.

5. In a paper-machine, the combination of the vacuum-boxes or suction-boxes, an inclined pipe discharging from the first box or boxes before the dandy into the discharge-pipe of the last after the dandy, whereby the boxes are successively primed by the charged suc-

tion-water from the first box, a graduating suction-pump for drawing the water through the discharge-pipes, and a pipe discharging from the pump and raised on a level with the 5 suction-boxes to prevent siphoning, substantially as and for the purpose shown and set forth.

In testimony that I claim the foregoing as my own I have hereunto affixed my signature in presence of two witnesses.

JOHN JOSEPH MANNING.
